[57] CLAIM

The ornamental design for a water heater riser, as shown and described.

DESCRIPTION

FIG. 1 is a bottom perspective view of one embodiment of a water heater riser showing my new design;

FIG. 2 is a an enlarged partial top plan view of the central cavity portion thereof;

FIG. 3 is an enlarged partial bottom plan view of central raised portion thereof;

FIG. 4 is an enlarged partial top plan view of an edge cavity portion thereof;

FIG. 5 is an enlarged partial bottom plan view of an edge raised portion thereof;

FIG. 6 is a side elevational view thereof facing an edge raised portion;

FIG. 7 is a side elevational view thereof facing between adjacent edge raised portions;

FIG. 8 is a top plan view thereof; and,

FIG. 9 is a top plan view of another embodiment of a water heater riser showing my new design.

The water heater riser is formed of a single sheet of plastic and is intended primarily to position and support a water heater and its catch pan appropriately spaced from the walls of a corner and above the floor.
